Filed Apr. 30, 1974, Ser. No 465,521

Term of patent 14 years

Int. Cl. D17—01

U.S. Cl. D56—2

Fig. 1

FIG. 2

FIG. 3

FIG. 1 is a front and right side perspective view of an organ showing my new design;

FIG. 2 is a front elevational view; and

FIG. 3 is a right side elevational view, the left side being a mirror image thereof.

The rear of the organ is conventional. The top of the organ behind the music rest is planar and unornamented. The pattern on the fabric covering the lower front and side panels is continuous throughout these areas.

I claim:

The ornamental design for an organ, as shown and described.
